UNITED STATES PATENT OFFICE.

CHARLES W. RENEAU, OF BATON ROUGE, LOUISIANA, ASSIGNOR OF ONE-HALF TO
JAMES R. BANKSTON, OF ANGUILLA, MISSISSIPPI.

BOILER FEED-WATER DISTRIBUTER AND CLEANER.

1,383,153.

Specification of Letters Patent. Patented June 28, 1921.

Application filed August 10, 1918. Serial No. 249,338.

To all whom it may concern:

Be it known that I, CHARLES W. RENEAU, a citizen of the United States, residing at Baton Rouge, in the parish of East Baton Rouge and State of Louisiana, have invented new and useful Improvements in Boiler Feed-Water Distributers and Cleaners, of which the following is a specification.

This invention relates to feed water distributors and cleaners for steam boilers, the broad object in view being to provide efficient means for not only distributing the feed water to the boiler but for thoroughly cleaning out the mud, sediment, scale and other impurities from time to time as required.

In the ordinary construction of devices of the character referred to, it is extremely difficult to successfully and thoroughly clean out a boiler where the boiler is of considerable length. Therefore, I have devised means whereby the feed water pipe contained mainly within the water compartment of the boiler is adapted to be cleaned or blown out in sections or zones successively and one at a time enabling the full steam pressure to be exerted on such portions or zones successively until the entire feed water distributing pipe within the boiler has been thoroughly cleaned throughout the entire length thereof.

With the above and other objects in view, the invention consists in the construction, combination and arrangement of parts, as herein described, illustrated and claimed.

In the accompanying drawings:

Figure 1 is a fragmentary sectional view of a steam boiler furnace, showing the feed water distributor and cleaner of this invention.

Fig. 1^a is a detail vertical section taken through a portion of the structure shown in Fig. 1.

Fig. 1^b—1^b of Fig. 1^a.

Fig. 2 is an enlarged longitudinal section through a portion of the distributor and cleaner.

Fig. 3 is a vertical cross section through the same on the line 3—3 of Fig. 2.

Fig. 4 is a detail view of one of the supports for the distributor and cleaner.

Fig. 5 is a side elevation of the distributor, partly in section and parts being broken away.

Referring to the drawings, 1 designates the wall, preferably the rear wall of a steam boiler furnace, and 2 the shell of the boiler.

In carrying out the present invention, I arrange in the bottom of the water chamber or compartment of the boiler, a feed water distributing and cleaning pipe 3, which extends the full length of the boiler and between the opposite heads thereof, said pipe 3 being formed in a plurality of longitudinally aligned sections, which sections are connected and fastened together by dove-tailed joints 4 at the adjacent abutting ends thereof. The sections of the pipe 3 may be readily connected and disconnected in relation to each other, the sections being relatively short and thereby facilitating storage and transportation and also enabling the pipe to be thoroughly cleaned out when for any reason one or more sections of said pipe become choked to an extent which will render it impossible to clean out the same by steam pressure.

The pipe 3, as a whole, is formed with feed water distributing outlets 5 arranged at intervals in the length thereof and about equi-distantly from each other. The pipe 3 is also provided with longitudinally elongated steam and water inlets 6 arranged in spiral formation with relation to each other so that said inlets 6 may be successively presented, one at a time to the action of incoming water as will hereinafter appear. The pipe 3 is mounted within a tubular casing 7, which holds the sections of the distributing pipe 3 in perfect alinement with each other and prevents such sections from becoming displaced or disconnected at their dove-tailed jointed ends. The casing 7 is formed in any desired number of sections as shown in the drawings and where the ends of said sections abut, I place a clamping member or strap 8 around the joint as shown in Fig. 3, there being as many straps or clamps 8 as there are joints in the casing 7. Each clamping member or strap 8 is formed in sections having flanges 9 and 10 through which are inserted clamping bolts 11, said bolts also passing through flanges 12 of the sections of the casing 7 and also through the lower and substantially parallel downwardly extending portions 13 of the casing 7, as shown in Fig. 3. Inclosing the structure thus far described is a housing 15, the shape of which is illus-

trated in Fig. 3, said housing being made in sections provided at the top with flanges 16 to receive clamping bolts 17. The lower edges of the sections of the housing 15 are secured to a longitudinal series of supports 18, approximately secured at 19 to the bottom of the boiler upon the inside thereof. The lower edges of the housing 15 terminate at the points 20 above the bottom of the boiler so that water may pass under said edges and through the longitudinally elongated passage way 14 to the interior of the pipe 3.

Adjacent to one end, the pipe 3 is inclosed within and passes through a connecting pipe 21 which is threaded at its outer end beyond the outside wall 35 of the furnace structure and has secured thereto a coupling 22 to which is connected a feed water supply pipe 23 and a blow off connection 24. Fastened to the adjacent end of the pipe 3 is a rotatable operating shaft 25 which passes through a stuffing box 26 on the coupling or fitting 22. Fast on the shaft 25 beyond the fitting 22 is a gear 27 shown as of the internal type, and meshing with said gear is a pinion 28, fast on a crank shaft 29 provided with a manually operable crank handle 30, the shaft 29 being journaled in a supporting standard or bearing 31 to which is connected by a pivot 32 a locking pawl or detent 33 which is adapted to engage in a circular series of notches 34 in the periphery of the gear 27 for the purpose of holding the gear 27 and therefore the pipe 3 in a number of different predetermined positions so as to effect an accurate registration of the inlets 6 with the passage 14 and also effect an accurate registration between the outlets 5 of the pipe 3 and corresponding outlets 5' in the tubular casing 7, the latter in order that the feed water may be distributed in the boiler. The notches 34 form graduations in order to enable the operator to accurately position and lock the gear 27 and therefore the pipe 3. 35^a designates an end thrust ball bearing for the shaft 2 and the distributing and cleaning pipe 3. The pipe 3 is additionally provided with a circular series of longitudinally elongated slots or openings 36 at a point between the feed water supply pipe 23 and the blow off connection 24. It will, of course, be understood that the pipes 23 and 24 will, as usual, be controlled by cut off cocks to be used in feeding water to the boiler and for blowing off the boiler.

In the operation of the device hereinabove described, the valve controlling the feed water inlet 23 is first closed. Then by means of the crank handle 30, a partial rotative movement is imparted to the operating shaft so as to cause one of the end inlets 6 of the pipe 3 to register with the passage 14. The valve of the blow off connection

is then opened and after that the pipe 3 is intermittently turned by means of the crank handle 30 so as to successively present the inlets 6 to the passage 14. When the pipe 3 has completed a revolution all of the inlets 6 have been successively presented to the passage 14 and the distributing outlets 5 are again in simultaneous registration with the outlets 5' of the tubular casing 7. The feed water supply pipe valve may then be again opened and water allowed to flow through the distributing pipe and also through the blow off connection until all of the scale, sediment, mud, and precipitation have been eliminated, after which the blow off valve is closed. This clears the blow off valve from scale and other material so destructive to the life and usefulness thereof.

The openings 6 allow for the passage of water from the annular space between the pipe 3 and the casing 7, allowing the water to circulate back and forth and thereby preventing excessive pressure between the pipe and casing. Extending longitudinally of 90 and within the casing 3 is a spirally twisted knocker or hammer 37 preferably made in sections as shown in Fig. 2, the sections being connected together by coupling means 38. The knocker or hammer 37 is not secured to any other element. On the other hand it is loose and unattached, being merely arranged in the casing 3. As the pipe 3 revolves, the knocker or knocker bar 37, because of the friction between the pipe or casing 3 and the bar 37 and also because of gravity, turns about its axis or moves sidewise in and against the pipe or casing 3 and is also agitated by the water and serves to dislodge any deposits or foreign matter 100 within said pipe, allowing the latter to be blown off and thereby keeping said pipe and casing clean and clear of obstructing matter.

I claim:—

1. In means for the purpose described, the combination of a pipe, means to turn the pipe about its axis, and a knocker bar loosely disposed longitudinally in the pipe and in contact with the wall thereof whereby turning of the pipe will be attended by movement of the knocker-bar in and against the pipe.

2. The combination with a steam boiler, of a feed water distributing pipe extending lengthwise of the bottom of the water compartment of the boiler and having distributing outlets at intervals in its length and also having water inlets at intervals in its length, said pipe being composed of separable longitudinally aligned sections having dovetailed joints, a tubular casing inclosing said pipe and having openings with which said outlets are adapted to simultaneously register, a feed-water supply pipe communicating with said distributing pipe, 130

a blowoff connection communicating with said distributing pipe, and means for admitting water to said inlets one at a time whereby different sections of said distributing pipe may be blown out successively.

3. The combination with a steam boiler, of a feed water distributing pipe extending lengthwise of the bottom of the water compartment of the boiler and having distributing outlets at intervals in its length and also having water inlets at intervals in its length, and arranged in spiral formation, a tubular casing inclosing said pipe and having openings with which said outlets are adapted to simultaneously register, a feed-water supply pipe communicating with said distributing pipe, a blow-off connection communicating with said distributing pipe, means for rotating said distributing pipe to successively present said inlets for the admission of water, the last named means comprising a shaft extending from one end of said distributing pipe outside of the furnace, and manually operable means for rotating said shaft, an element of said manually operable means being graduated to enable the positions of the inlets and outlets to be accurately gaged.

4. The combination with a steam boiler of a feed water distributing pipe extending lengthwise of the bottom of the water compartment of the boiler and having distributing outlets at intervals in its length and also having water inlets at intervals in its length, and arranged in spiral formation, a tubular casing inclosing said pipe and having openings with which said outlets are adapted to simultaneously register, a feed-water supply pipe communicating with said distributing pipe, a blow-off connection communicating with said distributing pipe, means for rotating said distributing pipe to successively present said inlets for the admission of water, the last named means comprising a shaft extending from one end of said distributing pipe outside of the furnace, a standard, an interiorly toothed and exteriorly notched wheel fixed on said shaft, a detent on the standard to enter said notches, and a shaft journaled in the standard and having a pinion intermeshed with the teeth of the wheel and also having a crank.

In testimony whereof I affix my signature.

CHARLES W. RENEAU.
